UNITED STATES PATENT OFFICE

ALLAN H. JONES, OF TRENTON, NEW JERSEY, ASSIGNOR TO ROLLER BEARING COMPANY OF AMERICA, OF TRENTON, NEW JERSEY, A CORPORATION OF NEW JERSEY

FEEDER

Application filed February 19, 1930. Serial No. 429,800.

This invention relates to a feeder which is designed and adapted to feed articles such as roller bearings to a grinding or finishing machine.

5 The principal object of the invention is to provide a feeder of the indicated character of simple and practical construction, and one which is continuous in operation.

10 The nature of the invention and its distinguishing features and advantages will appear when the following specification is read in connection with the accompanying drawing, in which

15 Figure 1 is a vertical section of the feeder embodying the features of the invention, the section being taken on the line 1—1 of Figure 2;

20 Figure 2 is a horizontal section taken on the line 2—2 of Figure 1;

25 Figure 3 is an enlarged fragmentary section taken on the line 3—3 of Figure 4;

30 Figure 4 is an enlarged fragmentary section taken on the line 4—4 of Figure 2.

Referring now more particularly to the 35 drawings, it will be apparent that the feeder includes a rotor or disk 10, secured in any practical manner to the upper end of a shaft 11 supported for rotation in any suitable manner. In the present instance the shaft 11 is vertically disposed and the lower end thereof is received in a bearing 12 on a base 13. The rotor or disk 10 is of stepped construction having a continuous circumferential upper surface 14 below the major upper flat sur-

35 face 15 thereof. A stator shell or circular part 16 fits around the circumferential edge of the disk, there being sufficient clearance between the shell 16 and the disk 10 to allow the latter to freely rotate within the former.

40 The disk 10 in its relationship to the shell 16 constitutes a bottom for the shell. The shell 16 is supported in a stationary position in any suitable manner such as by legs 17 secured at their upper ends to the shell, and the lower ends thereof being secured to the base 13.

45 The shell 16 has a discharge passageway 18 extending tangentially with respect to the circumferential edge or periphery of the disk 10. A rigid feed tube 19 is detachably connected as at 20 with an enlargement 21

through which the passageway 18 extends, so as to form a continuation of the passageway 18.

The disk shaft 11 may be rotated in any suitable manner at the desired speed. As shown in the drawings, the shaft is rotated by an electric motor 22 and driving means between the motor shaft and the shaft 11, said means being designated in general by the reference numeral 23.

50 From the foregoing it will be apparent that when articles, such as roller bearings of cylindrical form, are placed on top of the disk 10, they will be caused to move outwardly by centrifugal force imparted by the rotational movement of the disk 10. The roller bearings 24 are designated 55. As the bearings 24 are moved outwardly by the centrifugal force imparted by the disk 10 they will encounter the shell 16. Some of the bearings 24 will fall onto the circumferential surface 14 and be directed into the entrance end of the passage 18 one after the other. In this connection it is to be understood that the disk 10 will rotate in a counter-clockwise direction, as 60 seen in Figure 2. The bearings 24 are guided through the passageway 18 into the tube 19 in end to end relation in contact with each other and are forcibly fed from the tube 19 into the presence of suitable rotary grinding 65 or finishing elements constituting appurtenances of the grinding or finishing machine, 70 not shown in the drawings.

Claims:

1. In a feeder, the combination of a disk 75 rotor of stepped construction, a stator shell surrounding said rotor, said shell having a discharge passageway extending tangentially with respect to the periphery of the rotor, to receive and guide articles delivered thereto 80 from the rotor by the rotational movement of the rotor.

2. In a feeder, the combination of a disk of stepped construction rotatable on a vertical axis, a stationary shell surrounding said disk, 95 said shell having a discharge passageway extending tangentially with respect to the periphery of said disk, to receive and guide articles delivered thereto from the top of said disk by the rotational movement of the disk, 100

3. In a feeder, the combination of a disk rotatable on a vertical axis, said disk having a continuous circumferential upper surface below the major upper surface of the disk, a stationary shell fitting around the circumferential edge of the disk, said shell having a discharge passageway extending tangentially with respect to said edge to receive and guide articles delivered thereto from 10 said circumferential upper surface of the disk by the rotational movement of the disk.
